NOBLE S. CLAY, OF WILKINSBURG, PENNSYLVANIA, ASSIGNOR TO WESTINGHOUSE ELECTRIC & MANUFACTURING COMPANY, A CORPORATION OF PENNSYLVANIA.

ORNAMENTAL ARTICLE AND METHOD OF PRODUCING THE SAME.

Application filed June 25, 1919. Serial No. 306,617.

To all whom it may concern:

Be it known that I, NOBLE S. CLAY, a citizen of the United States, and a resident of Wilkinsburg, in the county of Allegheny and State of Pennsylvania, have invented a new and useful Improvement in Ornamental Articles and Methods of Producing the Same, of which the following is a specification.

10 My invention relates to the formation of ornamental articles and it has, for its primary object, the provision of a method for molding an ornamental surfacing to an article.

15 Heretofore, it has been customary to ornament articles by stenciling or transferring suitable ornamental designs, insignia, trade marks and the like, in the desired color or colors, directly upon the article to be ornamented. While, in many cases, this method is satisfactory, in numerous instances it does not result in a decoration that is as permanent and clear as may be desired, because of lack of adhesion between the pigments or 20 dyes and the material of the article to be ornamented. Furthermore, the ornamentation, being disposed directly upon the surface of the article, is exposed and liable to injury, either through wear or abrasion.

25 While my invention is applicable to the ornamentation of articles of numerous kinds and formed of various materials, it is primarily intended for use in ornamented articles formed of fibrous material and a hardened binder, such as a phenolic condensation product, and particularly articles of this character in which the fibrous material comprises superimposed sheets of paper or woven material, such as duck. I have found 30 that it is practically impossible to obtain a lasting ornamental article of this character by the usual methods of stenciling or transferring the design to the surface of the finished product because of the poor adhesion 35 between the pigments or dyes employed and the material of the article which possesses a naturally smooth and polished surface.

40 One object of my invention, therefore, resides in providing a method, for overcoming these difficulties, of such character that the ornamentation is disposed beneath a transparent or translucent surfacing provided for the article being ornamented, so that perfect adhesion is secured and so that 45 the ornamentation is protected from injury. 55 Another object of my invention resides in providing a method of ornamenting bodies of the nature referred to which permits the application of the desired ornamentation during the forming of the body itself. 60

With these and other objects in view, my invention will be more fully described, illustrated in the drawings, in the several views of which corresponding numerals indicate like parts, and then particularly 65 pointed out in the claims.

In the drawings, Fig. 1 is an elevation of a propeller provided with an ornamental insignia in accordance with my invention; Fig. 2 is a plan of a plate of fibrous material and a binder, provided with a fanciful design through the practice of my invention; Fig. 3 is a corresponding view showing how I may imitate the grain of wood, and Fig. 4 is a sectional view of a composite plate together with additional surface-forming sheets by means of which I may secure the desired decorative effect. 70

75 My present invention is particularly adapted for ornamenting or decorating composite bodies comprising superimposed layers of fibrous sheet material impregnated with a suitable binder, such as a phenolic condensation product, which may be rendered hard and substantially insoluble and infusible by the application of heat and pressure, and one of its chief advantages resides in the fact that the desired ornamentation may be applied to the article during the 80 curing of its binder. 85

90 In practising my invention, I may print, or otherwise provide, the desired ornamental design or ornamentation in any preferred color, or colors, upon a sheet of fibrous material, such as paper, which may be white or tinted, as desired. This ornamented sheet may then be disposed between sheets of fibrous material impregnated with a phenolic condensation product and the sheets thus assembled may be disposed upon the assembled 100 but uncured body of the article to be ornamented. The sheets, between which the ornamented sheet is disposed, may be of any suitable material which possesses sufficient transparency or translucency, either under 105 natural conditions or, at least, after it has been impregnated and cured, to disclose, with sufficient clearness, the design upon the

sheet disposed between them. I have found that very thin paper, when impregnated with the phenolic condensation product, is well suited for this purpose.

5 After these protective sheets and the interposed ornamented sheet have been disposed upon the uncured body to be ornamented, the article, together with the superposed sheets, may be cured in the usual manner by subjecting it to heat and pressure to compact the material and to transform the binder to its final, hard and solid state. This is usually done by subjecting the body to heat and pressure in a suitably shaped mold.

15 Obviously, the foregoing process may be applied to the ornamentation of articles of many kinds and of widely different materials. For example, in Fig. 1 of the drawing I have disclosed a propeller 1 which may 20 be formed of superimposed layers of fibrous sheet material and a binder, such as a phenolic condensation product, and which is provided with an insignia 2 applied to one of its blades.

25 In Fig. 2 I have illustrated a plate or block 3 of corresponding material provided with a fanciful design 4 which may be of any suitable outline and color or colors. Furthermore, the main surface of the plate may be 30 given any desired color while the design itself may be of a contrasting color or colors. Again, in Fig. 3 I have shown a block or plate 5 ornamented to imitate the grain of wood, as shown at 6. These examples are 35 illustrative only and are not intended as, in any way, indicating the scope of application of my invention.

Referring more particularly to Fig. 4 of the drawing, I have disclosed an assembled plate comprising superimposed layers of fibrous sheet material, such as duck, indicated at 7, impregnated with a suitable binder, such as a phenolic condensation product. Disposed above the body thus assembled (and spaced therefrom and from each other, for the sake of clearness,) are protective sheets 8 which may comprise thin sheets of tissue paper impregnated with a phenolic condensation product and an interposed sheet 9 upon which is printed or otherwise provided the desired ornamentation or design in any preferred color or colors.

15 The body thus assembled may be brought to suitable shape and its binder may be cured by subjecting the body to heat and pressure between the platens of a press, if the body be in plate form, or in a suitably shaped mold if the body has curved or irregular surfaces.

While I have shown the body of the plate as comprising duck and a binder, any other well known sheet material employed in the construction of articles of this character 5 may be employed with equally good results.

Among such materials are woven fabrics of various characters, as cotton batting and paper.

In some instances, it may not be necessary to employ a protective sheet between the 70 ornamented sheet and the body of the article to be ornamented, although I find that, as a rule, a more perfect adhesion of the ornamental surfacing is obtained by the employment of this sheet.

75 If the surface upon which the ornamental surfacing is to be molded is curved or irregular, it may be advisable to apply the ornamental sheet and its protective sheets to a sheet or group of superimposed sheets of 80 the material to be utilized in forming the body of the article and to slightly heat and compress the superimposed sheets thus assembled to provide a "preformed" composite sheet which may be superimposed upon other 85 treated sheets to provide the desired body which may then be cured in the usual manner. This will prevent tearing or wrinkling of the ornamented sheet or of its protective sheets during the molding operation.

90 If this is done, a sheet of untreated material should be disposed between the press plate and the sheet or sheets of treated material upon which the ornamented sheet and its protective sheets are disposed during the 95 preforming to protect such sheet from dirt and grease. This untreated sheet may be readily pulled off after the preforming to expose a clean surface for engagement against the remainder of the body to be 100 molded so that strong adhesion between the preformed and non-preformed portion of the body may result from the final molding.

105 Although I have described my invention with particular reference to the ornamentation of a body of fibrous sheet material and a binder, it will be obvious that the ornamented sheet, with its protective sheets, may be applied directly to the surface of any article of a material which will not be injured 110 by the heat and pressure required in curing the binder of the protective sheets and may be molded to such surface with equally good results. My invention may, therefore, be practised in ornamenting sheet metal in imitation of wood work or in providing wood-work with any desired decorative designs in any color or colors. My invention is not limited to the mere ornamentation of a body but is broad enough to include useful designs, diagrams and the like applied to various metallic and non-metallic bodies. For example, diagrams of electrical connections and instruction charts may be applied to various instruments and apparatus such as 115 120 meter cases and the like. Identification charts and nameplates made in accordance with my invention may be applied to various machines and apparatus.

125 In case the article being ornamented is of 130

a material other than a fibrous filler and a binder, it may be desirable to interpose several of the protective sheets between the ornamented sheet and the article to provide the latter with a harder and more durable surface.

From the foregoing description, it will be apparent that my invention is one of wide scope and that its application is not to be limited to any particular articles or materials. In fact, no limitations are to be imposed upon it other than those indicated in the claims.

I claim as my invention:—

- 15 1. The method of ornamenting a body which comprises disposing sheet material provided with the desired ornamentation between sheets of thin material impregnated with a binder, disposing the assembled sheets 20 against the body to be ornamented and curing the binder.
- 25 2. The method of ornamenting a body, of fibrous material and a binder which may be hardened under heat and pressure, which comprises forming the desired ornamentation upon a sheet of fibrous material, disposing the sheet so prepared between sheets of thin fibrous material impregnated with a binder, disposing the sheets so assembled 30 against the body and subjecting the body and superimposing sheets to heat and pressure to compact them and harden their binder.
- 35 3. The method of ornamenting a body, comprising fibrous sheet material and a phenolic condensation product as a binder, which comprises assembling a body of such material, impregnating a transparent or translucent sheet of fibrous material with a 40 phenolic condensation product, providing an untreated sheet with the desired ornamentation, interposing such sheet between the body and the impregnated sheet and subjecting the whole to heat and pressure to harden 45 the binder.

4. The method of ornamenting a body which comprises forming the desired ornamentation upon a sheet of paper, disposing the ornamented sheet between sheets of thin paper impregnated with a phenolic condensation product, disposing the sheets so assembled upon the surface of the body and subjecting them to heat and pressure against the body to harden the binder. 50

5. The method of forming an ornamented article which comprises impregnating fibrous sheet material with a phenolic condensation product, impregnating sheets of thin, translucent paper with a phenolic condensation product, forming the desired ornamentation upon a sheet of paper, disposing the ornamented sheet between certain of the thin paper sheets and upon certain of the first mentioned sheets, subjecting the sheets thus assembled to slight heat and pressure to cause adhesion between them, forming a body of the first mentioned sheets with the slightly pressed sheets disposed at its surface, and subjecting the body thus assembled to heat and pressure to harden the 65 binder and shape the article. 70

6. An ornamental article comprising a body of superimposed layers of fibrous material and a hardened binder and an ornamented sheet disposed below one of the layers of the body and visible therethrough. 75

7. An ornamental article comprising a body formed of fibrous sheet material and a phenolic condensation product, the sheet material being disposed in superimposed layers, and at least a portion of the outermost of one of the layers being transparent, and an ornamented sheet disposed between the transparent sheet and the other layers of the body. 80 85

In testimony whereof, I have hereunto subscribed my name this 19th day of June, 1919.

NOBLE S. CLAY.
